AXIAL FLOW JET MOTOR WITH REVERSELY ROTATING CONTINUOUS COMBUSTION TYPE COMBUSTION PRODUCTS GENERATOR AND TURBINE

Donald W. Seifert, Winona, Minn.

Application January 20, 1947, Serial No. 722,988

22 Claims. (Cl. 60—39.35)

1

This invention relates to jet motors.

In a co-pending application filed by me January 20, 1947, Serial No. 722,987, I have disclosed and described a form of jet motor and its principle of operation.

The present disclosure includes certain developments not included in the above-mentioned application. For purposes of convenience, the following is a statement of the general nature of a jet motor and may refer to subject matter common to both the previously mentioned invention, and the present, after which a statement of the improvements of the present invention follows.

The jet motor of the present invention is of the type which is propelled by expulsion of gases rearwardly out of the motor, and which picks up air for combustion when traveling. This is distinguished from rockets in which the air for combustion is contained in the fuel provided in the device.

By way of general explanation the present invention applies to that type of fuel burning device in which the device is propelled forward by rearward expulsion of gases of combustion; the gases of combustion in the same propelling process rotate a driving element which in turn operates a compressor. The compressor then picks up air in the travel of the device, compresses it, and delivers it to the driving element where it supports combustion of the fuel.

An important advantage resides in this feature; in previous jet propelled devices, the combustion chamber was stationary, and the gases of combustion were then driven through a turbine which operated a compressor. In the device of the present invention, a plurality of combustion chambers are arranged in a rotating driving means, where the combustion takes place, so that the actual process of combustion produces a direct and immediate rotating force on the driving means.

The combustion driving means above referred to may also be referred to as an "athodyd" or "athodyd stage." "Athodyd" is a word recently coined from aero-thermo-dynamic-duct, and applies particularly to jet motors. This driving element may be referred to herein both as an athodyd driving means and a combustion driving means.

A portion of the power generated by the expulsion of gases out of the motor is utilized in driving the compressor, but the air compressed by the compressor accomplishes more rapid combustion, resulting in higher speeds of the device.

Accordingly, the efficiency of such a device is increased as the speed of the motor is increased.

2

This is a peculiarity of jet motors, and because of that condition, when the efficiency drops to a certain point, operation of the device ceases. As a correlative of this phenomenon, the device must be given an impulse by some auxiliary force to attain initial speed for the jet propulsion feature to become effective.

The present invention utilizes an elongated cylindrical casing; a shaft is rotatably mounted centrally of the casing, and the compressor and athodyd stage mentioned above are rotatably mounted on the shaft. The casing is open at both ends taking in air at one end and expelling it at the other end.

15 Fuel is supplied to the athodyd driving means and an ignition device is provided for initial starting of the device. After the motor operates for a short time, the athodyd driving means becomes heated and the heat therefrom ignites the fuel; thereafter the ignition system is no longer required.

Another phenomenon peculiar to jet motors is that while both ends are open, the expulsion of gases is effected in only one direction, such expulsion being in the same direction as the influx of air which is brought in by the travel of the machine. The incoming air is compressed inside the motor and drives the gases of combustion out the opposite end.

20 An advantage of the present invention, as distinguished from my previously mentioned invention, is that it includes a compressor having inner and outer rotary elements, and an athodyd driving means having inner and outer rotating driving elements. The rotary elements of the compressor are driven by respective elements of the athodyd driving means.

The provision of counter rotating elements of a compressor delivers higher pressure of air, and the provision of separate elements in the combustion driving means distributes the power for greater efficiency.

25 Another advantage of the present invention is that gearing of different ratios may be interposed between the respective elements of the athodyd driving means and the compressor to obtain different relative speeds between the parts.

30 With these and other objects in view, my invention consists in the construction, arrangement and combination of the various parts of my device whereby the objects contemplated are attained, as hereinafter more fully set forth, pointed out in the claims and illustrated in the accompanying drawings, in which:

Figure 1 is a longitudinal sectional view of one form of my invention;

Figure 2 is a longitudinal sectional view of another form of the present invention;

Figure 3 is a view taken approximately on line 3-3 of Figure 1;

Figure 4 is a view taken approximately on line 4-4 of Figure 1;

Figure 5 is a view taken substantially on line 5-5 of Figure 1;

Figure 6 is a view taken substantially on line 6-6 of Figure 1;

Figure 7 is a diagrammatic developed view of the blades and buckets of the turbocompressor, taken substantially on line 7-7 of Figure 1; and

Figure 8 is a longitudinal sectional view of a compressor and air sealing means therefor.

Figure 9 is a fragmentary view of a modified form of the inner and outer rotor combination illustrated in Figure 1.

Figure 10 is a view taken substantially on line 10-10 of Figure 9.

The device of Figure 1

Referring in detail to the drawings, the jet motor of Figure 1 includes a cylindrical elongated casing 12 having an outwardly flaring open inlet end 14, and an outlet end 16 tapered rearwardly along air-flow lines and terminating in a substantially cylindrical outlet opening 18. If desired, the casing 12 can be tapered along air flow lines to produce more efficient air flow, and the working parts designed to conform to the shape of the casing. A shaft 20 is rotatably mounted axially in the casing in bearing supports 22 and 24. The bearing support 22 has a central opening for the shaft 20 and a sleeve supporting shaft 20 which will be referred to later, and includes a central portion 26 and radial fins 28 extending outwardly from the central portion 26 and secured to the casing 12. The bearing support 24 includes a central portion 30 and radial fins 32 extending outwardly from the central portion 30 and secured to the casing 12.

A turbocompressor indicated generally at 34 is rotatably mounted on the shaft 20. The compressor 34 includes a central rotary element 36 which may be fixedly secured to the shaft 20, and includes a plurality of sets of blades 38 extending radially outwardly therefrom. The compressor 34 also includes an outer rotary element 40 in the form of a hollow drum 41 surrounding the inner rotary element 36. Extending inwardly from the inner peripheral surface of the drum 41 are a plurality of sets of buckets 42 disposed alternately between adjacent sets of blades 38. The blades 38 and buckets 42 are curved oppositely from each other, as shown in Figure 7, for more efficient compression action. The outer rotary element 40 includes end plates 44 secured to sleeves 46 and 48 which are freely rotatable on the shaft 20. The plates 44 have outwardly extending radial fins 50 which are connected to the drum portion 41 of the outer rotary element 40. The sleeve 46 is fitted in the central opening of the bearing support 22 and the sleeve 48 is positioned in the central opening of the bearing support 24. The plates 44 may be secured to the drum 41 and respective sleeves in any well known manner.

The athodyd driving element is indicated generally at 52, and includes a central or inner driving element 54 fixedly secured to and rotatable with the shaft 20. The inner driving element 54 comprises a drum-like portion 56 hav-

ing an annular space 58 formed therein adjacent its outer periphery. Secured to the outer surface of the drum 56 are a plurality of blades 60 extending radially outwardly therefrom. Formed in each blade 60 is a passage 62 which communicates with the annular space 58 and terminates in jets 64 opening out of the blade tangentially therefrom. The shape and positioning of the blades 60 will be referred to later.

An outer driving element is indicated generally at 66 and includes a hollow ring-like member 68 disposed outwardly beyond the inner driving element 54, and having an annular space 70. Positioned on the inner surface on the ring-like member 68 is a plurality of blades 72 of a shape symmetrical with the blades 60, but being differently disposed, and extending down to and in proximity with the outer tips of the blades 60. Leading from the spaces 70 through the blades 72 are passages 74 terminating in jets 76 opening out of the respective blades tangentially thereof and into the spaces therebetween.

The ring-like member 68 is secured to a spider-like member indicated generally at 78 (see Figure 4). The member 78 includes a plurality of arms or fins 80 having outer segments 82 and inner segments 84. A ring 86 is formed on or connected with the joints between the segments of the fins 80. The inner segments 84 are connected to a hub 88 which is formed on or connected to sleeve 48 for rotation therewith in any convenient manner.

Fuel is supplied to the combustion driving means through an inlet passage 90 on the exterior of the device. The passage 90 leads down through one of the fins 82 and the central portion 80 of the bearing support 24 as indicated at 92. Passage 92 then communicates with the passage 94 in the sleeve 48, which communicates with passage 96 formed in the shaft 20. The passage 94 in the sleeve 48 is provided at its opposite ends with annular recesses to communicate with passages 98 and 92 in all positions of rotation of the various elements. The passage 96 in the shaft 20 then communicates with a passage 98 which leads outwardly through the central part of the driving element 54 and finally communicates with the annular space 58 in the driving element 54. It will be recalled that from the annular space 58, passages 62 and jets 64 lead from the tubes 61 to and open into the spaces between the blades 60.

Another passage 100 is formed in the sleeve 48 and leads from the passage 94 axially of the sleeve 48 and then outwardly through the hub 88 and fins 80 in the outer driving element 68 and finally communicates with the annular space 70 in that driving element.

Auxiliary outlet openings 102 lead from the passage 92 in the bearing support 24 and open toward the athodyd driving means 52. One such outlet opening 102 is associated with each driving element 54 and 66. Solenoid closure means 104 are provided for opening and closing the outlets 102. A Venturi-shaped ignition glow plug 106 is disposed at the outlet of each opening 102, through which fuel passes on emerging from the openings 102. An ignition circuit 108 is provided for operating the ignition means 106 and the solenoid operated closure 104.

A shield 110 surrounds the sleeve 48 at the leading end of the device for forming an annular inlet area 111 conforming to the annular space occupied by the blades 38 and buckets 42 and deflecting air therethrough. Similarly, another

shield 112 is formed at the rear and secured to the shaft 20. The shield 112 covers the central portion of the inner driving element 54 forming an annular outlet area 113, and tapers rearwardly to a point, conforming generally with the contour of the trailing end 16 of the device.

Operation of the device of Figure 1

As mentioned hereinabove a jet motor must be started by some auxiliary force for the mechanism to become effective. This may be done by connecting an auxiliary motor to the contra rotating shafts 20 and 46 for initiating rotation thereof.

After the initial starting force is applied and the motor driven to a predetermined speed, the compressor 34 is driven by the driving means 52. Referring to Figure 5, the blades 72 are peculiarly shaped, forming the athodyd spaces 73 between adjacent blades. Each space 73 has an enlarged intermediate portion 114 and a restricted dimension 115 at the right end, or inlet, and another restricted dimension 116 at the left end, or outlet. Outwardly beyond the restricted dimensions 115 and 116 are outwardly diverging spaces 117 and 118. When fuel is injected into the spaces 114 and ignited therein, the gases of combustion are expelled rearwardly out through the restrictions 116. Such rearward expulsion occurs when pressure is built up in the forepart of the spaces 114, and this expulsion out of the rear of the device drives the device forward, and at the same time, the expulsion of combustion gases out of the spaces 73 imparts a rotary motion to the blades 72, and thus also rotates the driving element 66.

Comparison of Figures 5 and 6 will show how opposite rotation of the driving elements 54 and 66 is accomplished. Figure 5 shows the angular relation of the blades 72 whereby, when gases of combustion are expelled rearwardly out of the spaces 73, rotation of the driving element 66 is toward the reader as observed in Figure 5. In Figure 6 it will be noted that the angular disposition of the blades 60 is in the opposite direction from the blades 72, with respect to the direction circumferentially of the device. Expulsion of gases of combustion out of the restrictions 116 in the spaces 73 in Figure 6 will rotate the driving element 54 in a direction away from the observer as viewed in Figure 6.

Driving element 66 is connected with outer rotary element 40 of the compressor through sleeve 48; and driving element 54 is connected with inner rotary element 36 of the compressor through shaft 20. It will therefore be seen that opposite rotation of the driving elements produces opposite rotation of the rotary elements of the compressor.

When the device is initially started as by means of an auxiliary motor, the compressor 34 builds up air pressure and delivers it rearwardly toward the driving means 52. Fuel is injected in the passage 90 which finds its way to the jets 64 and 76 and into the spaces 114 between the respective blades 60 and 72. Also in the starting operation, the solenoid operated closure 104 is opened, permitting fuel to emerge out of the outlets 102, and the ignition means 106 are operated for igniting fuel emerging from the outlets 102. This ignites the fuel emerging from the jets 64 and 76 as well, since the outlets 102 are in close proximity to the spaces 115 and 117.

After a predetermined speed is attained and a predetermined length of time expires, the

blades 60 and 72 become heated and the heat from these blades is sufficient to ignite the fuel. At this point the ignition means 106 may be cut out. Upon sufficient pressure being built up by the compressor 34, the gases of combustion in the driving means 52 are forced rearwardly out of the device. This rearward expulsion forces the motor forward, increasing the action of the compressor, and increasing the efficiency of the driving element in such a manner that each feature adds to the action of the other, resulting in increasing speed and efficiency.

The tangential disposition of the jets 64 and 76 produces an added turning force on the respective driving elements 54 and 66 of the athodyd driving means. The reaction against the blades 60 and 72 from the pumped fuel emerging from the jets adds to the force of combustion in rotating the driving means, similar to the action of a lawn sprinkler.

The action of the compressor 34 in compressing air and delivering it to the rear is well known to those familiar with turbines and turbocompressors. Figure 7 shows the curvature and relative angles of the blades 38 and the buckets 42. This relative angularity delivers compressed air toward the rear, or left, and through the athodyd driving means 52. It will be understood that since the separate elements of the driving means 52 rotate in opposite directions, that streams of air must be directed in opposite directions circumferentially of the device into the respective driving elements 54 and 66, for greater efficiency. The fins 32 of the bearing support 24 are given opposite directions of inclination midway between their outer and inner extremities. The outer extremities of the fins 32 are shown at 120 in Figure 5, are streamlined in cross-section and are directed in nearly the same angular relation as the blades 72. The portions 120 of the fins 32 therefore form a stream of air and deflect it directly toward the diverging spaces 117 and into the spaces 114. The blades 72 rotates in a direction against such stream of air and the shape of the diverging spaces 117 is such as to readily scoop up the air from that stream.

Due to the opposite rotation of the inner driving element 54, the inner portions 122 of the fins 32 are angled in the opposite direction (compare Figures 5 and 6). The portions 122 thereby form a stream of air and deflect it circumferentially of the device in a direction opposite to that deflected by portion 120, and since the blades 60 are rotating in the opposite direction from the blades 72 they scoop up the air from the latter stream readily.

To accommodate these separate streams of air the fins 80 in the outer driving element 66 have a peculiar formation. The outer segments 82 of the fins 80 are streamlined in cross-section as indicated in Figure 5. These fins 82 rotate with the blades 72 (since they are connected therewith) and do not add to or detract from the passage of air therebetween.

However, the inner segments 84 of the fins 80, which are adjacent the blades 60 of the inner driving element 54, rotate in the direction opposite the blades 60. It is therefore necessary to form the segments 84 differently from the segments 82. These segments 84 cannot be given a streamlined shape, and be disposed at the same angle as the blades 60, because at this angle the direction of rotation of the segments 84 might tend to have a backing-up effect on the air-stream, unless they were traveling at one partic-

ular speed. Therefore, to accommodate different speeds, these segments 84 are formed round in cross-section to have as little effect as possible on the flow of air therewith.

If desired, a tube or cylinder 200 may be secured to the inner ends of the blades 72 and a tube or cylinder 202 may be secured to the outer ends of the blades 60, to prevent air from being churned between the two sets of blades.

It will be noted that in the device of Figure 1 the inner rotary element 36 of the compressor and the inner driving element 54 of the driving means are directly connected with the shaft 20 and therefore rotate in unison. Also, the outer rotary element 40 of the compressor and the outer driving element 66 of the driving means are directly connected through the sleeve 48 and therefore rotate in the same direction with each other, and opposite to their counterparts. It may be desirable to impart various speeds to the various elements, and to accomplish this result reference may be had to the form of the device of Figure 2.

In the initial starting of the device, efficiency will be improved by imparting an impulse to both the shaft 20 and the sleeve 46 thereon, in opposite directions, to rotate both rotary elements of the compressor 34, and consequently both driving elements of the combustion driving means 52.

The shaft 20 may be utilized as an auxiliary output shaft for operating auxiliary power plants, such as the lighting system on a ship on which the device can be used. Similarly, the sleeve 46 may be used as an auxiliary output shaft.

The device of Figure 2

Figure 2 includes gearing means for providing driving connection between the driving means 52 and the compressor 34. Such gearing and its adaptations will be described in detail in Figure 2, and those features of Figure 2 which are similar to Figure 1 will not be dwelt upon in detail.

The turbocompressor 34 of Figure 2 includes an inner rotary element 36 which instead of being directly connected with the shaft 20 is secured on a sleeve 124. The sleeve 124 is freely rotatable on the shaft 20 and extends rearwardly where a ring gear 126 is secured thereto. Meshing with the ring gear 126 are a plurality of planetary gears 128 supported in the bearing support 24; and meshing with the planetary gears 128 is a sun gear 130 fixedly secured to the shaft 20.

Fixed to the outer rotary element 40 of the compressor, and extending rearwardly therefrom, is a tubular extension 132 in the outer end of which is formed a ring gear 134. Meshing with the ring gear 134 are a plurality of planetary gears 136 mounted on the bearing support 24. A sun gear 138 is arranged to mesh with the planetary gears 136 and is fixed on the forward end of sleeve 140. The sleeve 140 corresponds with the sleeve 48 in Figure 1 and is connected with the outer driving element 66 of the driving means 52, in any suitable manner.

It will be noted that the inner driving element 54 of the driving means 52 has driving connection with the inner rotary element 36 of the compressor, and likewise, the outer driving element 66 of the driving means 52 has driving connection with the outer rotary element 40 of the compressor. The relative rotation of the counterparts of the compressor and of the driving means are the same as in Figure 1, although the driving connections are through gearing instead of being direct as in Figure 1. The gearing may be

varied, as to speed ratios, for increasing or decreasing the relative rotation of the parts of the compressor.

Although the rotation between the counterparts of the compressor and of the driving means is the same in connection with Figs. 1 and 2, the interconnected elements between the compressor and driving means rotate oppositely, i. e., the outer driving element 66 of the driving means rotates oppositely from the outer rotary element 40 of the compressor, and the inner driving element 54 of the driving means rotates oppositely from the inner rotary element 36 of the compressor. Accordingly, in the device of Figure 2, the blades 38 and buckets 42 will be reversed in direction of their pitch, as will the fins 28.

Reference may be had to Figure 3 for a means for preventing the passage of air through the device around the outside of the compressor. The casing 12 is provided with an enlarged portion 142 for accommodating the compressor 34. The outwardly flaring inlet portion 14 is of about the same diameter as the inner diameter of the drum 41 of the outer rotary element 40 of the compressor. It is naturally desirable to have all of the air passing through the device to pass through the compressor, and to that end an angle member 144 is secured to the inner surface of the casing 12 in the enlarged portion 142, and in engagement with the outer rotary element 40 of the compressor. This prevents air from passing through the spaces 146 outwardly of the outer rotary element 40 of the compressor, and deflects all of the air through the compressor.

The efficiency of the device is improved due to the fact that combustion takes place directly in the rotary driving means. This is distinguished from previous types of jet motors where gases passed from a stationary combustion space to a turbine driving element with consequent loss of efficiency. In the present device such loss of efficiency is eliminated.

Although I have herein shown and described certain preferred embodiments of my invention, manifestly they are susceptible of modification and rearrangement of the parts without departing from the spirit and scope thereof. I do not, therefore, wish to be understood as limiting my invention to the precise forms herein disclosed, except as I may be so limited by the appended claims.

I claim as my invention:

1. In a jet motor, a casing having open ends adapted for flow of air therethrough, a shaft rotatable in said casing, an inner rotor mounted on said shaft, an outer rotor mounted on said shaft and having a portion overlapping said inner rotor, a first set of blades extending generally radially from said inner rotor toward said overlapping outer rotor portion, a second set of blades extending generally radially from said overlapping outer rotor portion toward said inner rotor, each of said two sets of blades being formed with fuel passages therein terminating tangentially of said blades for injecting fuel in the spaces between adjacent blades, each of said two sets of blades extending radially short of the ends of the opposed set of blades and with their leading edges offset from their trailing edges in a direction opposed to the direction of offsetting in the opposed set whereby said rotors are caused to rotate in opposite directions, and means for supplying fuel through said passages.

2. A jet motor according to claim 1 having rotor blades whose sides are concave over a portion of

their axial length from their leading edges to their trailing edges.

3. A jet motor according to claim 1 comprising stationary vanes extending radially therein ahead of said rotors and having their trailing edges offset from their leading edges in the same directions as the blades of said rotors downstream thereof.

4. A jet motor according to claim 1 comprising an outer rotor having a hub mounted on said shaft and radial projections connecting said hub with the outer rotor portion overlapping said inner rotor, said radial projections being formed ahead of said outer rotor blades as vanes having their leading edges offset from their trailing edges in the same direction as the outer rotor blades.

5. A jet motor according to claim 4 in which said radial projections have a substantially round cross sectional form between said hub and said vanes.

6. A jet motor according to claim 1 comprising a bearing for said shaft and radial bearing support projections from said bearing connecting the bearing to said casing and formed with fuel passages therein, said outer rotor having a central hub rotatable on said shaft and radial rotor supporting projections from said hub connected to the overlapping outer rotor portion, said hub and the radial rotor supporting projections being formed with fuel passages therein communicating with the fuel passages in said outer rotor blades and with the fuel passages in said bearing support projections and said shaft being formed with fuel passages therein communicating with the fuel passages in said inner rotor and with the fuel passages in said bearing support projections.

7. In a jet motor, a casing having open ends adapted for flow of air therethrough, a shaft rotatable in said casing, an inner rotor mounted on said shaft, an outer rotor mounted on said shaft and having a portion overlapping said inner rotor, a first set of blades extending generally radially from said inner rotor toward said overlapping outer rotor portion, a second set of blades extending generally radially from said overlapping outer rotor portion toward said inner rotor, the leading edges of each set of rotor blades facing axially in the same direction and being spaced axially forward of their trailing edges, each of said two sets of blades extending radially short of the ends of the opposed sets of blades and with their leading edges of each set of blades offset from their trailing edges in a direction opposed to the direction of offsetting in the opposed set of blades.

8. A jet motor according to claim 7 having rotor blades whose faces are concave over a portion of their axial length.

9. A jet motor according to claim 7 having rotor blades formed with fuel passages therein terminating on the trailing faces of said blades and pointing in a direction opposite to the direction of rotation of said blades, said motor further comprising means for supplying fuel to said passages.

10. A jet motor according to claim 9 wherein the rotor blade fuel passages terminating on said trailing face point in a direction having a component tangential to said trailing face.

11. A jet motor according to claim 9 having rotor blades whose faces are concave over a portion of their axial length and having the rotor blade fuel passages opening at said concave portion of the blade face.

12. A jet motor according to claim 7 including at least one tubular element extending axially of said motor between the opposed sets of rotor blades.

13. A jet motor as set forth in claim 7 including at least one tubular element extending axially on said motor between the opposed set of rotor blades and said tubular element being secured to the tips of the blades of one of said rotors.

14. A jet motor according to claim 7 having rotor blades formed with fuel passages therein terminating on the trailing faces of said blades and pointing in a direction opposite to the direction of rotation of the rotor.

15. In a jet motor, a casing having open ends adapted for flow of air therethrough, a shaft in said casing, an inner axial flow rotor mounted on said shaft, an outer axial flow rotor mounted

20 on said shaft and having a portion overlapping said inner rotor, a first set of blades extending generally radially from said inner rotor toward said overlapping outer rotor portion, a second set of blades extending generally radially from said overlapping outer rotor portion toward said inner rotor, each of said two sets of blades extending radially short of the ends of the opposite set of blades, the axial component of air flow through each set of blades being in the same direction, and means including the shape of the blades of the rotors for causing said rotors to rotate in opposite directions.

16. A device as set forth in claim 15, wherein a portion of the faces of each blade are concave, whereby each pair of adjacent blades form an enlarged combustion chamber therebetween.

17. A jet motor as set forth in claim 15 comprising a set of radial projections between the shaft and the casing spaced upstream of the rotors, fuel passages in said inner and outer rotors and fuel passages in said radial projections communicating with the fuel passages in said inner and outer rotors.

18. In a jet motor, a casing having open ends adapted for flow of air therethrough, a shaft in said casing, an inner axial flow rotor mounted on said shaft, an outer axial flow rotor mounted on said shaft and having a portion overlapping said inner rotor, a first set of blades extending generally radially from said inner rotor towards said overlapping outer rotor portion, a second set of blades extending generally radially from said overlapping outer rotor portion towards said inner rotor, each of said two sets of blades extending radially short of the ends of the opposed set of blades, each blade of said inner and outer rotors having a leading face and a trailing face, and the leading face of each blade and the opposite facing trailing face of the previous blade being shaped to form therebetween a flow passageway having an enlarged combustion chamber formed intermediate the ends thereof.

19. A jet motor as set forth in claim 18 including fuel passages extending radially through said blades and terminating in jets positioned adjacent the outer tips of the blades and opening to said combustion chambers.

20. A jet motor as set forth in claim 18 including a throat in said flow passageway downstream of said combustion chamber, and an expansion nozzle downstream of said throat.

21. In a jet motor, a casing having open ends adapted for flow of air therethrough, a shaft in said casing, an inner axial flow rotor mounted on said shaft, an outer axial flow rotor mounted

11

on said shaft and having a portion overlapping said inner rotor, a first set of blades extending generally radially from said inner rotor towards said overlapping outer rotor portion, a second set of blades extending generally radially from said overlapping outer rotor portion towards said inner rotor, each of said two sets of blades extending radially short of the ends of the opposed set of blades, each blade of said inner and outer rotors having a leading face and a trailing face, the leading face of each blade and the opposite facing trailing face of the previous blade being shaped to form therebetween an axial flow passageway comprising, in order passing downstream, a first throat, a combustion chamber of enlarged width, a second throat, and an expansion nozzle.

22. In a jet motor, a casing having open ends adapted for flow of air therethrough, a shaft in said casing, an inner axial flow rotor mounted on said shaft, an outer axial flow rotor mounted on said shaft and having a portion overlapping said inner rotor, a first set of blades extending generally radially from said inner rotor towards said overlapping outer rotor portion, a second set of blades extending generally radially from said overlapping outer rotor portion towards said inner rotor, each of said two sets of blades extending radially short of the ends of the opposed set of blades, each blade of said inner and outer rotors having a leading face and a trailing face, the leading face of each blade and the opposite facing trailing face of the previous blade being shaped to form therebetween a flow passageway having an enlarged combustion chamber formed intermediate the ends thereof, the axes of said

12

5 combustion chambers being straight and disposed at an angle to the axis of the motor, a throat in each said flow passageway downstream of the combustion chamber and an expansion nozzle downstream of said throat, and the portion 10 of the blade leading face downstream of said throat extending axially of the combustion chamber axis further than the portion of the blade trailing face downstream of said throat, whereby the flow issuing from the flow passageway is turning toward a direction parallel to said motor axis.

DONALD W. SEIFERT.
